DRYING KILN

Clifford R. Guthrie, Spokane, Wash.

Application March 31, 1948, Serial No. 18,109

3 Claims. (Cl. 34—47)

1

The invention relates to drying kilns and an object of the invention is to provide a kiln comprising a specially designed building consisting of a steel frame and enclosed by insulated aluminum panels and doors arranged in such a manner that they do not obstruct or interfere with the predetermined currents of air created in said kiln building.

Another object of the invention is to provide a kiln of the character indicated above, the building of which contains the necessary apparatus for heating the air in said building comprising a fan or a blower to set the air into motion to flow through prearranged ducts and air ways while being directed by baffles.

A further object of my invention is to provide a kiln of the character indicated above, in which inlet dampers are automatically opened to permit a predetermined amount of fresh air to enter, when the used drying air contains a predetermined amount of moisture.

A still further object of the invention is to provide a kiln of the character indicated above, which is equipped with outlet dampers discharging any superfluous amount of air from the kiln.

Another object of my invention is to provide a kiln of the character indicated, in which the mixture of fresh air and pre-used drying air is forced through a humidifying chamber, where a controlled amount of humidity may be added to said air mixture before it starts again its circuit through the kiln.

Other objects of the invention may appear in the following specification describing it with reference to the accompanying drawing illustrating a preferred embodiment of the invention. It is, however, to be understood that the invention is not to be limited or restricted to the exact construction and combination of parts described in the specification and shown in the drawing, but that such changes and modifications may be made, which fall within the scope of the claims appended hereto.

In order that the invention may be better understood I will now proceed to describe it with reference to the accompanying drawing, in the several figures of which similar parts are indicated by similar reference characters and in which:

Figure 1 is a diagrammatical view showing a longitudinal section through the kiln according to the invention.

Figure 2 is a sectional view taken on line 2—2 in Figure 1.

Figure 3 is a sectional view taken on line 3—3 in Figure 1.

2

Figure 4 is an elevational outside view of a wall of the drying kiln according to the invention, and

Figure 5 is a sectional view in a larger scale 5 and taken on line 5—5 in Figure 4.

The drying kiln embodied herein comprises a building B of preferably elongated rectangular shape, on the floor 10 of which a plurality of comparatively long spacers 11 are arranged 10 parallel to each other and longitudinally of the building B. The spacers are spaced from each other at such a distance that each pair of adjacent pair parallel spacers is adapted to support a plurality of boards 12 or the like extending 15 transversely of the building and parallel to each other and spaced apart from each other as shown at 13. On top of these boards some more spacers 11 are placed longitudinally of the building and parallel to and spaced apart from each other, 20 and another tier of boards 12 or the like is arranged on top of each pair of the spacers resting 25 on the first described tier of boards. The boards in the second tier extend also transversely of the building and parallel to each other and are spaced from each other as shown. The stacks 15 of boards are arranged so that one end of one stack is located as a comparatively short distance from the end wall 14 of the building, that a space 15 is left between adjoining stacks 30 and that there is also a space between the stacks and each of the longitudinal walls 16 of the building B. A partition 17 extends transversely across the building and divides it into a drier room 18 and a heater room 19. There is left a space 20 between the partition 17 and the adjacent stack of boards.

In the heater room 19 an air heating device 21 of any preferred conventional kind and construction is arranged, which may heat air passing 40 therethrough either by means of oil, coal, high pressure steam coil or the like. A fan 22 sucks the heated air out of the heater and blows it through a supply duct 23, which extends upwardly through the ceiling 24 of the building 45 B and horizontally and longitudinally in the attic 25 between the ceiling and the roof 26. On the inner end portion of the supply duct a pair of branch ducts 27a are arranged, which extend downwardly through the ceiling 24 into the drier room 18 approximately centrally between the end wall 14 and the partition 17. On the end portion of each branch duct two high velocity registers or air nozzles 27b are mounted 50 at a level above the top tier of the boards 12. The nozzles are arranged so that they expel heated air toward the end wall 14 and the par-

tion 17 and the expelling force is such that the expelled air hits the wall and the partition without coming into direct contact with the stacked lumber. The heated air is then deflected toward the floor 10, thus building up a pressure. To prevent the heated air from flowing around the stacks S narrow vertical baffles 28 are arranged on the longitudinal side walls 16, so that they project inwardly therefrom and abut the outer corner portions of the stacked boards. Between the boards located adjacent the space 15 a baffle plate 29 is arranged adjacent each side wall 16 and closing the ends of the space 15. The heated air, which is expelled through the nozzles 27b flows therefore through the spaces formed by the spacers 11 between the stacked boards toward the center as indicated by the arrow heads in Figure 1.

In the central space 15 a portion of the heated air flows upwardly, where it combines with the air being expelled from the nozzles 27. The biggest portion of the air in the space 15 is sucked by the force of the fan 22 through an opening 30 in the floor 10 into a return duct 31 arranged underneath the floor. This return duct is connected with a mixing chamber 32 located in the heater room 19. An air inlet 33 extending through the roof 26 is normally closed at its bottom end by dampers 34 preventing fresh air from entering the mixing chamber. When the return air has absorbed enough moisture from the lumber being dried to contain a predetermined amount of moisture, the dampers are opened by any conventional means, such as an electro-magnet for instance, controlled by a conventional hygrostat 35 or the like. The entering fresh air mixes with a portion of the air flowing through the return duct. The air in the mixing chamber is sucked by the fan 22 through a duct 36 into a humidifying chamber 37. Here the mixed air is further humidified to a predetermined degree, if required, by conventional hygrostat control means (not shown). From there the air is drawn into and through the heater 21 for another cycle.

The superfluous portion of the return air passes the entrance to the mixing chamber 32 and keeps on flowing through the return duct 31, which extends beyond the end wall 38 of the heater room 19 and projects then upwardly and outwardly as indicated at 39 and 40 respectively. The end opening of the return duct portion 40 may be closed by outlet damper 41. A drain pipe 42 is connected with the return duct 31 and leads to a pit 43 so that any condensed water collecting in said return duct flows off through said drain pipe.

To make the above described drying kiln highly effective, it is necessary to build up a certain amount of pressure, so that the heat will penetrate the lumber better to open the pores and to start the sap to flow more freely. To attain this object the building B is constructed as follows:

A frame F consists of a plurality of vertical frame members 44. Each of these members has a substantially square cross-section and is provided on one of its sides with a longitudinal slot 45. The frame members are mounted in vertical position so that the slotted sides of the members face inwardly of the house B. Insulated aluminum panels P are built up, by forming hollow bodies from two sheets 46 of aluminum, which are connected with each other by end and side walls, consisting each of a strip of aluminum. The hollow in each of these bodies is filled with

any preferred heat insulating material 47. The panels are secured to the vertical frame members by carriage bolts 48 slipped into the slot 45 and extending through said slots and between 5 two adjacent panels P held against the inside or slotted face of the frame member. An elongated plate 49 of aluminum is provided with a plurality of equidistantly spaced holes 50 permitting the bolts 48 to extend therethrough. 10 Nuts 51 on said bolts force the plates 49 clampingly against the panels P and hold them in position. Any open spaces in the walls constructed, as described above, are filled with any preferred conventional mastic. The walls may be reinforced by cross frame members 52 extending 15 transversely between the vertical frame members 44.

The above description shows clearly that a kiln building of the character described eliminates all 20 obstructions adapted to cause any deflection of the air currents, since all the panels are secured on the inside of the frame members.

I claim:

1. A lumber drying kiln, comprising an elongated building including end and side walls, a floor and a roof, a transverse partition dividing the interior of the building into a drying room and a smaller heater room, a ceiling extending above the two rooms to provide an attic between the same and the roof, a heater within said heater room, an air mixing chamber within said heater room and communicating with said heater, an air inlet depending through the roof and said ceiling and communicating with said mixing chamber, a main duct extending from said heater through said ceiling and the attic to a point above the approximate center of said drying room, a branch duct extending transversely from the free end of said main duct, nozzles extending from the opposite sides of said branch duct, a suction fan mounted within said heater adjacent the inlet end of said main duct for forcing the heated air through the latter to said nozzles, said nozzles being adapted to discharge the heated air laterally therefrom toward the opposite ends of said drying room for its circulation over and back through lumber arranged in spaced tiers within the latter, an air return duct extending beneath the floor and opening therethrough at the approximate center of said drying room, and a second branch duct extending upwardly through the floor into said heater room from said return duct and communicating with said mixing chamber.

2. The invention as defined in claim 1, with the said return duct having its outlet end extending beyond the second branch duct and the outer end wall of said heater room, said outer opening to atmosphere by way of an upwardly and outwardly angled extension thereof, damper means mounted within said extension, and a drain leading from said return duct at the lower end of said extension.

3. The invention as defined in claim 1, with a humidifying chamber interposed between said air mixing chamber and said heater, damper means mounted within said air inlet adjacent its point of connection with said air mixing chamber, and a hygrostatic control means within said mixing chamber for regulating the admission of fresh air thereto.

CLIFFORD R. GUTHRIE.
